ATTORNEY.

UNITED STATES PATENT OFFICE

2,272,035

RAILWAY CAR TRUCK

Robert B. Cottrell, Chicago, Ill., assignor to
American Steel Foundries, Chicago, Ill., a corporation of New Jersey

Application January 13, 1940, Serial No. 313,724

4 Claims. (Cl. 105—197.2)

My invention relates to quick wheel change trucks and more particularly to methods of preventing accidental dismantling of quick wheel change trucks of the type disclosed in my United States Letters Patents 2,188,641 and 2,220,218, issued on January 30, 1940 and November 5, 1940, respectively.

The general object of my invention is to prevent accidental dismantling of such quick wheel change trucks by interlocking the bolster column insert means with the bolster.

Another object of my invention is to provide a novel method of preventing accidental disengagement of the bolster from the side frame of such a truck.

A different object of my invention is to prevent looseness and rattling between the bolster column inserts and the bolster.

My invention further contemplates safety arrangements for such a quick wheel change truck as will meet all of the manufacturing requirements and service conditions normally contemplated in railway freight car trucks.

Figure 1 is a fragmentary side elevation of a truck embodying a different modification of my invention, partly in section, said section being taken substantially in the vertical longitudinal plane bisecting the side frame.

Figure 2 is a fragmentary top plan view of the structure shown in Figure 1.

Figure 3 is a fragmentary end view of a bolster and insert showing a different modification of my invention, one-half being shown in section, the section being taken substantially in the vertical plane indicated by line 3—3 of Figure 4.

Figure 4 is a fragmentary top plan view of the structure shown in Figure 3.

Figure 5 is a fragmentary end view of a bolster and insert showing a different modification of my invention, only one-half of the bolster end being shown inasmuch as the other half is similarly arranged, and Figure 6 is a fragmentary sectional view of the modification shown in Figure 5, said section being taken substantially in the horizontal plane indicated by line 6—6 of Figure 5.

Figure 7 is a fragmentary end view of a bolster and insert showing a different modification of my invention, only one-half of the bolster end being shown inasmuch as the other half is similarly arranged, and Figure 8 is a fragmentary sectional view of the modification shown in Figure 7, said section being taken substantially in the vertical plane indicated by line 8—8 of Figure 7.

One method by which I may prevent accidental dismantling of the bolster and side frame is to secure the insert or inserts to the bolster in such manner that the bolster and insert will act as a unit. When the bolster is raised to its uppermost position where it is out of engagement with said flanges, the insert, acting as a unit with said bolster, retains its engagement with said flanges and thus prevents accidental disengagement of the bolster and side frame. Various modifications illustrating this method are shown in Figures 1 to 8.

In Figure 1 is shown a fragmentary portion of a well-known type of truck including a truss side frame with the compression member 4, the tension member 6, and the integral column 10 forming therewith an opening through which may project the end of the bolster 12. Centrally formed spaced lugs 50, 50 on the insert member 51 project upwardly through the rectangular opening 52 in the bottom wall of the bolster 12 and receive therebetween the bolster center reinforcing rib 26. Aligned holes in said lugs and said rib receive a nut and bolt assembly 53 which secures said insert to said bolster.

In Figures 3 and 4, a centrally formed boss 54 on the insert member 55 projects upwardly through an opening 56 in the bottom wall of the bolster and into the relieved portion 58 in the center rib 26. A diagonal opening may be formed adjacent the top of said boss in which a pin may be inserted thus securing said insert to said bolster. In the modification shown in Figures 5 and 6, a substantially rectangular shaped rib 60 joining the upstanding end portion 61 and the base of the insert member may be formed in place of a triangular rib, such as disclosed in my before-mentioned patents. Said rib may have an opening 62 to receive a pin to fix the insert member to the bolster.

In Figures 7 and 8 each spaced U-shaped strap 70 formed on the insert 71 projects upwardly through a rectangular opening 72 in the bottom wall of the bolster. The opening 74 formed by said strap extends above the top surface of the bottom wall of the bolster so that a resilient member 76 having a shallow recess 77 on its upper surface may be inserted in the opening 74 in such manner that the recess locks with said strap and prevents separation of the insert and the bolster.

It is to be understood that I do not wish to be limited by the exact embodiments of the device shown which are merely by way of illustration and not limitation as various and other forms of

the device will, of course, be apparent to those skilled in the art without departing from the spirit of the invention or the scope of the claims.

I claim:

1. In a quick wheel change truck, a truss side frame having a top member, a bottom member and spaced columns defining therebetween a bolster opening, guide means on said columns, a spring seat on said bottom member beneath said opening, resilient means seated thereon, interlocking means positioned on said resilient means and having engagement with said guide means, a bolster end seated on said interlocking means and having widened portions engaging said guide means, whereby said bolster end and said interlocking means cooperate as a unit with said guide means, said guide means being spaced from said top member a distance approximately equal to the depth of said widened portion, whereby said bolster may be raised and disengaged from said guide means while said interlocking means remains in normal operative position in engagement with said guide means, and means including a central boss on said interlocking means for securing said interlocking means to said bolster so that when said bolster disengages with said guide means the engagement of said interlocking means with said guide means prevents accidental disengagement of said bolster and side frame.

2. In a quick wheel change truck, a truss side frame having a top member, a bottom member and spaced columns forming therebetween a bolster opening, guide means on said columns, a spring seat on said bottom member beneath said opening, resilient means seated thereon, interlocking means positioned on said resilient means and cooperating with said guide means, a bolster end seated on said interlocking means and engaging said guide means, whereby said interlocking means and said bolster end cooperate as a unit with said guide means, said guide means being spaced from said top member a distance such that said bolster end may be raised and disengaged from said side frame while said interlocking means remains in normal operative position in engagement with said guide means, and safety means cooperating with said bolster end and said interlocking means to prevent accidental dismantling of said bolster end and said side frame when said bolster is raised to its maximum vertical position, said safety means comprising a boss centrally located on said interlocking means and extending through the bottom wall of said bolster end for securement therewith.

3. In a four wheel truck, a side frame having a top member, a bottom member, and spaced column guides defining a bolster opening, a bolster end with a central reinforcing rib projecting through said opening and having approximately the top half thereof widened to form lateral shelves, guide flanges on said columns, channels on said widened portions having engagement with said guide flanges, and an interlocking member having its ends seated against said shelves and presenting channels in alignment with said before-mentioned channels and also having engagement with said flanges, said guide flanges being spaced from the tops of said columns a distance approximately equal to the depth of said shelves whereby said bolster end may be elevated from said interlocking member and disengaged from said guide flanges while said interlocking member remains in normal operating position, and a central upstanding boss on said interlocking member projecting within said bolster end into a relieved portion of said central rib and adapted to receive means securing said interlocking member to said bolster for preventing accidental dismantling of said bolster and side frame when said bolster disengages from said guide flanges.

4. In a four wheel truck, a side frame having a top member, a bottom member, and spaced column guides defining a bolster opening, a bolster end with a central vertical rib projecting through said opening and having approximately the top half thereof widened to form lateral shelves, guide flanges on said columns, channels on said widened portions having engagement with said guide flanges and an interlocking member having its ends seated against said shelves and presenting channels in alignment with said before-mentioned channels and also having engagement with said flanges, said guide flanges being spaced from the tops of said columns a distance approximately equal to the depth of said shelves whereby said bolster end may be elevated from said interlocking member and disengaged from said guide flanges while said interlocking member remains in normal operating position, and a central member on said interlocking member projecting through the bottom wall of said bolster, accommodated within a relieved portion in said central rib, and adapted to receive means securing said interlocking member to said bolster end whereby accidental dismantling of said bolster and side frame is prevented when said bolster disengages from said guide flanges.

ROBERT B. COTTRELL.
